UNITED STATES PATENT OFFICE.

CHARLES M. PEACOCK, OF CHICAGO, ILLINOIS.

TIME SWITCH.

Application filed October 2, 1926. Serial No. 139,048.

This invention relates to improvements in time switches and it consists of the matters hereinafter described and more particularly pointed out in the appended claims.

6 The primary object of the invention is to provide an efficient and compact device substantially of alarm clock size and appearance, and of such simplicity as to be operable by the average person to control the switching 10 operations or "on" and "off" periods for the circuits of electrically operated devices such as radio receiver sets, electric household appliances, and show window and sign illumination.

15 A further object of the invention is to provide such a device, the operation cycle of which is based on impulse movements instead of continuous movements, whereby a more positive action is provided and whereby the 20 operations of the devices controlled by the switch may be more positively and accurately started and stopped at definite time periods known in advance to the setting of the switch.

These objects of the invention, as well as 25 others together with the many advantages thereof will more fully appear as I proceed with my specification.

In the drawings:

Fig. 1 is a view in front elevation of a time 30 switch embodying my invention as coupled up with a radio receiving set to control the periods of reception thereof.

Fig. 2 is a view in rear elevation of the switch as coupled with a plurality of lamps 35 to control the periods of illumination afforded thereby.

Fig. 3 is a sectional view through a make 40 and break circuit device embodied in my improved time switch with parts thereof broken away to more clearly show the interior construction thereof, the plane of the section being indicated by the line 3—3 of Fig. 5.

Fig. 4 is a fragmentary view in elevation 45 of one of the fixed contacts embodied in the make and break circuit device shown in Fig. 3.

Fig. 5 is a vertical section through my improved time switch as taken on the line 5—5 of Fig. 1.

Fig. 6 is a transverse vertical detail section 50 view through the switch as taken on the line 6—6 of Fig. 5.

Fig. 7 is a detail sectional view through parts shown in Fig. 6 as indicated by the line 7—7 thereon.

Fig. 8 is a detail sectional view through a 88 part of the switch as indicated by the line 8—8 of Fig. 13.

Fig. 9 is a fragmentary view in elevation of an impulse dial and parts associated therewith embodied in the improved time switch. 90

Fig. 10 is a vertical section through the parts shown in Fig. 9 as taken on the line 10—10 thereof.

Figs. 11 and 12 are detail views in elevation of coacting parts for turning the indicator shaft in one direction only and which will be more specifically referred to later. 95

Fig. 13 is a transverse vertical sectional view through the switch as indicated by the line 13—13 of Fig. 5. 100

Fig. 14 is a detail sectional view through parts shown in Fig. 13 as indicated by the line 14—14 of said Fig. 13. 105

Fig. 15 is a view in plan elevation of the parts shown at the top end of Fig. 14. 110

Figs. 16 and 17 are detail sectional views on an enlarged scale as taken on the line 16—16 and 17—17 respectively of Fig. 6 and which will be more fully referred to later. 115

Fig. 18 is a detail perspective view on an 120 enlarged scale of part of an escapement mechanism embodied in my improved switch with the elements thereof in one position.

Fig. 19 is a view in elevation on an enlarged 125 scale, of the parts shown in Fig. 18 when in another position and which will be more fully referred to later.

Fig. 20 is a transverse sectional vertical 130 view through the switch as taken on the line 20—20 of Fig. 5.

Fig. 21 is a detail sectional view as taken on the line 21—21 of Fig. 20. 135

Fig. 22 is another detail sectional view as taken on the line 22—22 of Fig. 20.

Fig. 23 is a further detail sectional view as 140 taken on the line 23—23 of Fig. 20.

Fig. 24 is a fragmentary view in elevation 145 of parts shown in Fig. 20 but in a different position.

Fig. 25 is a fragmentary sectional view of a 150 modified form of impulse mechanism which may be embodied in my improved switch, the plane of the section being indicated by the line 25—25 of Fig. 26.

Fig. 26 is a detail sectional view as taken on 155 the line 26—26 of Fig. 25.

Fig. 27 is another detail sectional view as taken on the line 27—27 of Fig. 25.

Fig. 28 is a detail view showing a modified arrangement of the rotary contact driving mechanism and which will be more fully described later.

5 Referring now in detail to that embodiment of the invention illustrated in Figs. 1 to 24 inclusive of the accompanying drawings:— My improved switch is embodied in a casing similar to an alarm clock and which comprises an annular front casing part 1 and an annular rear casing part 2. The front casing part includes an annular wall 3 and a flat upright rear wall 4, the annular wall having a radial flange 5 at its front end of enlarged diameter. The rear casing part includes an annular wall 6 and an upright flat rear wall 7, the annular wall at its front end fitting over the rear end of the casing part 1 as best shown in Fig. 5. On the vertical median line at the top of the casing wall 7 is an opening 8 the purpose of which will more fully appear later. Extending radially from the annular wall 3 of the casing 1 at the bottom thereof are feet 3^a—3^a and extending 10 rearwardly and downwardly from the bottom portion of the rear wall of the rear casing 2 is a third foot 2^a all of said feet providing a stable base for the casing as a whole. Within the rear casing part 2 and spaced adjacent the rear wall 7 thereof is an upright plate 9 supported in the proper position by means of long studs and nuts 10 extending between the rear walls 4 and 7 of said casing parts. Projecting forwardly from the casing wall 4 in axial alignment with the casing part is a fixed non-rotative bushing 11 of 15 substantially large diameter.

30 The open front end of the casing part 1 is closed, by a dial supporting plate 12 having its peripheral portion offset forwardly as at 12^a and with a portion 12^b spaced radially inward therefrom, offset rearwardly to provide an annular track the purpose of which will appear later. On the plate 12 within the 35 offset portion 12^a is a dial 13 covered by a suitable glass 14. The dial is divided into twelve hour divisions by radial lines 13^a and each hour division is subdivided into quarters (instead of fifths as in ordinary clocks) by radial lines 13^b. The lines 13^a—13^b thus together divide the dial into forty-eight divisions, each indicating one quarter of an hour or fifteen minutes. This manner of dividing the dial is only arbitrary and is to 40 be taken as by way of explanation only and not by way of limitation. Appearing on the dial is a circular arrow 13^c which begins and ends at that radial line designating the ninth hour which arrow indicates the beginning 45 duration and ending of the cycle during which a certain switch escapement later to be described is free to close the circuit to be controlled at a given setting. This stated hour is just arbitrary. In the portion 12^a of 50 the dial plate is provided inner and outer

concentric rows of openings 15 and 16 respectively with the openings disposed in the radial planes of the division lines 13^a—13^b on the dial. Journalled coaxially in the dial plate 12 is a bearing member 17 which is 55 fixed to the front end of a spindle or shaft 18. The rear end of said spindle bears in an opening in the plate 9 and fixed thereto is a bushing 18^a. Said bushing carries a disc 19 (between the plate 9 and rear wall 7) and said disc has a notch 19^a (see Fig. 20) and rotative on that end of the spindle beyond the bushing is a knob 20 having a tooth 20^a to enter the notch 19^b. In this manner it is only possible to turn the spindle 18 in a clockwise 60 direction. A nut 18^c is threaded onto the spindle end to prevent complete withdrawal of the knob from the spindle. On the extreme front end of the spindle 18 is fixed an indicator or hand 21 in a manner to cooperate with the division markings on the dial 13. Fitted on the spindle 18 between the member 17 and bushing 18^a, respectively, is a tube 22 which is capable of a limited endwise movement on said spindle. On the rear end of said 65 tube is an annular pallet engaging shoulder 22^a and on the front end of said tube is a radial flange 22^b.

70 Journalled in the front end of the non-rotative bushing 11 is a tubular bearing sleeve 23. Said sleeve carries at its front end a disc 24 having a forwardly extending annular flange 24^a in which is formed a plurality of arcuately spaced ratchet-shaped notches 24^b, there being one of such notches for each of the time divisions 13^a—13^b thus making in 75 all, forty-eight of said notches. On the rear side of said disc is an annular housing 25 including a radial flange having peripheral teeth to form a large spur gear 26. Within this housing is a flat spiral spring 27 the outer end of which is fixed to said housing and the inner end of which is fixed to a tubular sleeve 28 journalled on the front end of the non-rotative bushing 11.

80 The ratchet-shaped notches 24^b each have a rear straight face and a front inclined face and the words "rear" and "front" are only relative so far as the normal direction of rotation of said disc is concerned. These notches have two functions; the straight face driving the indicator 21 through a certain pawl means later to be described, in a clockwise direction under the action of the spring 27 while the front inclined face permits said 85 pawl means to be turned manually in a clockwise direction by means of the knob 20 independent of said notches. On the rear end of the sleeve 28 is secured a gear 29 which carries a pawl 33^a on its rear face. Said gear 90 meshes with a main winding gear 30 fixed to the forward end of a shaft 31 arranged parallel with the spindle 18 below and to one side thereof. This shaft is journalled in the casing wall 4 and plate 9 and is provided with a 95 100 105 110 115 120 125 130

key 31^a projecting beyond the casing wall 7 so that it may be turned to wind up the spring 27.

Also rotatively mounted on the bushing 11 to the rear of the sleeve 28 is a second sleeve 32 on which is fixed a ratchet 28^a and spur gear 33 (see dotted lines in Fig. 13). Said pawl 33^a engages the ratchet 28^a and holds the spring 27 against unwinding except when 10 it is driving a snap switch as will later appear when it unwinds from the inner end and from the outer end when driving the indicator. When the main spring is being wound up the pawl slips backwards over the ratchet. The 15 gear 33 meshes with a pinion 34 on a shaft 34 positioned parallel with and vertically above the spindle shaft 18. Said shaft which constitutes an escapement shaft is journaled at its inner or front end in a bushing fixed to the 20 casing wall 4 and its rear end extends through the plate 9 and through the opening 8 in the rear casing wall 7 to be journaled in the front wall 35^a of a circular switch casing 35. Said switch casing is mounted on the rear 25 casing wall 7 so as to cover the opening 8 and is supported by studs 35^b projecting rearwardly from the plate 9. On the shaft 34 between the casing wall 4 and plate 9 is an escapement device including two fan blades 34^b—34^c each carrying a pallet 34^d and 34^e respectively with the pallets disposed in longitudinally spaced planes as best shown in Fig. 5. Said pallets are adapted to engage the annular shoulder 22^a on the tube 22 which 30 is adapted to engage and hold the escapement, the pallet 34^d engaging the shoulder when it is at the limit of its movement rearwardly as shown in Fig. 5 and hereinafter referred to as the "off" pallet of this escapement and the 35 pallet 34^e engaging the shoulder when it is in its forward movement (as hereinafter described) and hereinafter referred to as the "on" pallet of this escapement.

The switch casing 35 which is closed at its 40 open rear end by an insulated cover 36 includes an annular wall 35^b on the interior of which is fixed a ring of insulation 35^c. In said casing are two oppositely disposed fixed contacts 37—38 the free ends of which are 45 made arcuate and are slit longitudinally to provide a plurality of yielding contact fingers 39 (see Fig. 4) whereby better contact engagement by a movable contact member is possible. Connected to each fixed contact is a 50 conductor 40—41 suitably hooked up in the circuit of the device or apparatus the "off" and "on" periods of which are to be controlled by the time switch as a whole. 42 indicates a 55 stud or shaft fixed coaxially in the front wall 85^a of the switch casing and extending rearwardly therefrom. Journaled in this stud or shaft is a bushing 43 and secured to the front end of said bushing is a gear 44 meshing with a pinion 45 on the rear end of the escapement shaft 34. Also fixed on said bushing is a 60 disc of insulation 46 of substantially the 70 interior diameter of the switch casing and rotative with said disc but insulated from the bushing by said disc is a rotative contact member including contact shoes or arms 47 and 48 respectively adapted to engage the 75 fixed contacts 37 and 38 in succession. On the marginal portion of the disc on the front side thereof are suitable markings 49 visible from the front of the time switch as a whole 80 through a sight opening 35^d in the rear wall of the switch casing. By said markings, which in this instance are the words "on" and "off", it is possible to visibly determine the position of the movable contact arms with 85 respect to the fixed contact arms and whether or not they are in engagement therewith. The gearing between the bushing 43 and shaft 34 is of a peculiar kind. The gear 44 is an elliptical gear and the pinion 45 is an ordinary spur pinion set eccentrically on the escapement shaft 34. The said gear and pinion so mesh that when the contact shoes engage the 90 fixed contacts and the resistance therefor is greatest, the major axis of the elliptical gear and the minor axis of the eccentric pinion are in line (see Fig. 3) and when said shoes are out of engagement with the fixed contacts and the circuit is open, then the minor axis of the 95 gear and the major axis of the pinion are in line and in this manner the switch torque is more nearly equalized and arcing materially reduced. The gearing is so correlated that when the shaft 34 makes one-half a revolution the switch arms will make one quarter of 100 a revolution. Therefore, when the tube 22 is moved forwardly the escapement pallet 34^d is released and the escapement fan turns (one half a revolution) until the pallet 34^e engages the shoulder 22^a when in its forward position 105 and is arrested thereby. Thus during this movement of the escapement the contact shoes have moved from "off" to "on" and when the tube 22 is again moved rearwardly the escapement is released for another half revolution 110 and the contact shoes move from "on" to "off" position.

Intermittent or step by step rotary impulse movement of the disc 24 under the action of the spring 27 is permitted or controlled by 115 an impulse mechanism as follows: 50 indicates a stub shaft extending forwardly from the casing wall 4 and journaled in a bushing 51 fixed in said wall. On the front end of said shaft is secured a pinion 52 meshing with the gear 26 on the spring barrel 25 all as best shown in Fig. 8. To the rear of this pinion and fixed to said shaft is an impulse escapement embodying two opposed 120 arms 53—54 each carrying inner and outer pallets 53^a—53^b and 54^a and 54^b respectively as best shown in Figs. 13, 18 and 19. The escapement is capable of one half a revolution at each instance of operation and the ratio of 125 the pinion 52 to the gear 26 is such that each 130

movement of the escapement permits of an impulse movement to the gear 26 and disc 24 corresponding to the angular distance between the markings on the dial 13 or the distance between the notches 24^b of said disc.

Mounted on the front face of the plate 9 on the right hand side of the time switch as a whole when viewed from the front is a clock mechanism of ordinary construction 10 and indicated as a whole by the numeral 55 in Fig. 20. Said movement includes a main spring arbor 56, an impulse cam shaft 57, and a counter shaft 58. The arbor projects through the rear casing plate 7 and is there provided with a winding key 59 (see Fig. 2) for easy manipulation and operatively connected to said arbor in the usual manner is a spring and gear 56^a and 56^b respectively. The gear meshes with a pinion 60 on the 20 counter shaft 58 which also carries a gear 61 and said gear in turn meshes with a pinion 62 frictionally mounted on the cam shaft 57. Associated with the pinion 62 is a gear 63 which meshes with other gearing 64 actuating the balance wheel and escapement 65 of said clock mechanism in the usual manner. The frictional drive between the shaft 57 and pinion and gear 62—63 is best shown in Fig. 10 and is similar to that used to drive the 30 minute hand of an ordinary alarm clock. In this instance said pinion and gear are yieldingly held against a shoulder 57^a in the shaft 57 by means of a spring disc 57^b interposed between a collar 57^c on the shaft and the rear 35 end of the pinion and gear. Thus the pinion may slip on said shaft only when a certain turning pressure is imposed on said shaft.

The forward end of said shaft 57 bears in a bushing 66 carried by the casing wall 4 40 while its rear end bears in a suitable opening in the plate 9. On said forward end of said shaft is fixed a cam 67 having a single notch or drop shoulder 67^a while on the rear end of the shaft is fixed a knob 68 carrying a pointer 68^a. This knob is arranged in a suitable opening 69 in the casing wall 7 and about said opening on said wall are disposed graduations 69^a.

Associated with the cam 67 is a lever 70 pivoted at 71 to a stud secured to the casing wall 4. The free end of said lever carries a pin 70^a projecting from one side of the same to bear and ride upon the periphery of the cam 67, and by turning the knob in the suitable direction, the relative angular position of the drop shoulder 67^a of the cam 67 with respect to the pinion 70^a of the same may be changed to either "advance" or "retard" the functioning of said cam as desired. A spring 72 fixed to said lever and to a pin 72^a on the wall 4 normally holds the lever so that said pin engages the periphery of the cam. On the opposite side of the free end of the lever 70 is a tooth 70^b to be engaged by the pallets 53^a and 53^b and 54^a and 54^b of the escape-

ment arms 53 and 54 respectively. In Fig. 19 the cam follower pin 70^a is shown as ready to trip over the cam shoulder 67^a and the tooth 70^b is engaged by the inner pallet 53^a—54^a of one of the escapement arms 53 70 and 54. When the pin 70^a drops over the shoulder 67^a it engages the low side of the cam and the tooth 70^b releases the inner pallet. The escapement arms then rotate and the outer pallet of the arm engages said tooth 75 and stops the rotation of the escapement which has made one-half revolution. As the cam 67 is turned, through the clock mechanism as before described, the follower pin 70^a is elevated and as the high portion of 80 the cam approaches the same, the pallet is free of the said tooth on the escapement arm and the inner pallet is again caught and held thereby. Thus there are two movements occurring in the release and catching of the escapement, a primary movement when the inner pallet is released and a slight secondary movement when the outer pallet is released and inner one is again caught. This secondary movement is of no particular value 85 in the time switch but is necessary to free the escapement pallets. As the escapement arms fly around a half a revolution, they permit the disc 24 and indicator to be rotated in a clockwise direction an angular distance equal to 90 the angular distance between adjacent notches 24^b or between the division 13^a—13^b on the dial 13. These movements of the indicator and disc are step by step or impulse movements as is desired. It is pointed out 95 that the clock mechanism imparts one complete revolution to the impulse cam shaft in fifteen minutes and that the only function of said mechanism to so move said shaft and it has no other function. 100

The inner and outer rows of openings 15 and 16 in the portion 12^a of the dial plate are intended to removably receive plugs or pins 73 as best shown in Figs. 1, 5, 16 and 17. Each plug includes a head 73^a and a split 110 body 73^b. The body which is cylindrical has a tapered inner end and inner and outer shoulders 73^c and 73^d, the inner shoulder being beveled at substantially a right angle to that of the taper of the body. The tapered 115 slit body permits the same to contract in diameter to freely enter a hole 15—16 and when the inner tapered shoulder has passed through said hole it tends to "bottom" the plug in the hole with the outer shoulder engaging the face of the plate part 12^a about said hole. Thus when such a plug is engaged in a hole 15—16 it cannot be accidentally displaced in operation and it does not fit so tight 120 therein as to be difficult to withdraw. 125

Means is provided which is rotative with the indicator hand 21 to engage those portions of the pins projecting rearwardly of the dial plate, and to impart an endwise movement to the tube 22 to automatically re- 130

lease and then stop the escapement arms 34^b and 34^c in succession. Such means comprises a flat lever 74 fixed to the member 17, just to the rear of the dial plate 12. Said lever is 5 formed to provide a longitudinally extending flange 74^a and inner and outer transverse flanges 74^b and 74^c all projecting rearwardly from said lever as best shown in Figs. 6 and 7. On the outer transverse flange is journaled 10 a roller 75 adapted for rolling engagement upon the track formed by the rear surface of the rearwardly offset portion 12^b of the dial plate. Secured to the inner transverse flange is a flat spring arm 76 which carries 15 a tooth for yielding engagement in the notches 24^b of the disc 24. Mounted on the longitudinal flange 74^a is a converter arrangement comprising a single lever 77 and a compound lever 78. The single lever is pivoted at a point between its ends on a screw 20 79 carried by the flange 74^a and the outer end thereof is formed to provide a plane or finger 77^a adapted to coact with the plugs 73 in the outer row of holes 16 while the inner 25 end is formed to provide a head 77^b to engage behind the flange 22^b of the tube 22. The compound lever includes a lever arm 78^a pivoted at a point between its ends on the screw 79 and a second lever arm 78^b pivoted on a 30 screw 79^a carried in the flange 74^a. The outer end of the lever arm 78^a is formed to provide a plane or finger 78^c adapted to engage the front face of the tube flange 22^b. The adjacent ends of the lever arms 78^a and 78^b are 35 operatively connected together so that when the plane or finger 78^c engages a plug 73 a movement in the same direction is imparted to the inner end of the lever arm 78^b to move the tube 22 rearwardly. It is apparent that 40 in the operation of the parts just described that when the finger 77^a engages one of the plugs 73 in the outer row of holes 16 which control the "on" periods said finger will climb over said plug and cause a rocking movement 45 of the single lever 77 whereby the head 77^b on the inner end thereof will engage the tube flange 22^b and move the tube forwardly. In the forward movement of said tube the shoulder 22^a moves to free the escapement arm 34^b 50 which then rotates 180° when the escapement arm 34^c engages and is stopped by said shoulder. In the rotation of the escapement arm the contact arms 47 and 48 in the switch casting 35 are rotated by the gears 44 and 45 to bring them into engagement with the contacts 37 and 38 and complete the circuit through the conductors 40 and 41. When the flat lever 74 has rotated sufficiently so that the finger 78^c of the compound lever 78 engages 55 a plug it will climb the same and rock the lever 78^a and 78^b. The lever 78^b will act to thrust or push the tube 22 rearwardly thus releasing the escapement arm 34^c and again catching or stopping the escapement arm 34^b. 60 In this movement of the escapement with the same the switch arms 47-48 move out of engagement with the contacts 37 and 38 and the circuit is broken and again "off". By means of the indicia 49 on the disc 46 of the switch, it is possible to at once ascertain visibly 70 whether the switch is in its "off" or "on" position.

It is here pointed out that the roller 75 takes up the thrust of the yielding tooth carrying arm 76 and in this way the flat lever 76 or converter as it may be aptly termed is securely held at both its ends and against any bodily yielding induced by the plugs as the lever sweeps over the same. The planes or fingers 77^a and 78^c are so oriented or related 80 with respect to the holes 15 and 16 in the dial plate that the ends of the path of travel of said fingers clear the holes on the advance sides thereof a short distance, say 1/64 of an inch. This not only permits the levers to move freely at all times but also permits certain manual controls later to be described to be operated immediately after the snap switch in the casing 35 has been turned on as before described. As shown in Figs. 16 and 20 90 17 the planes or fingers are made with two angles whereby the movement is gradual and at a high leverage when the shoulder 22^a is being forced from under the teeth of the escapement arms. During the remaining parts 95 of this movement of the shoulder after the same is free from either escapement arm tooth, the leverage is reduced as the resistance is reduced and in this manner the full efficiency of movement of said single and compound levers is utilized.

Under some conditions it might be desirable to manually trip the escapement so that the time switch may be actuated from "off" to "on" and vice versa at any time after it 105 has been brought from one position or the other. To manually change the switch positions from "off" to "on" I provide a yielding arm 80 which is fixed at its bottom end to the inner surface of the plate 9 in the vertical plane of the spindle 18 and offset forwardly of said plate as best shown in Fig. 5. The top end of said yielding arm is bifurcated to straddle the bottom portion of the spindle to the rear of the shoulder 22^a and has a forward 110 extension 80^a engaged with the rear side of said shoulder. Associated with said arm is a stem or button 81 fixed at its front end thereto and projecting at its rear end through a hole in the rear casing wall 7. On the projecting end of said stem is depicted the word "on" as shown in Fig. 2 to indicate that this is the member to be actuated when it is desired to manually change the switch condition from "off" to "on". By pressing inwardly on said button the top end of the arm 115 engages the rear end of the shoulder 22^a and moves it and the tube 22 forwardly and releases the shoulder from one escapement arm 120 pallet so that the escapement actuates the 125 130

switch to "on" position, when the shoulder 22^a will catch and stop the other escapement pallet and hold it in the "on" position of the switch. When pressure is released on 5 said button it springs back and stops under the action of a shoulder 81^a on said stem or button. To manually shift the tube 22 to bring the switch from the "on" to the "off" position I provide a yielding arm 82 fixed 10 at one end to the rear wall 4 of the front casing and offset forwardly between its ends to pass through an opening 4^a in said casing wall (see Fig. 21) so that its top end may project up through an opening 3^b in the casing 15 walls 3 and 6. In said arm in the plane of the tube 22 is a suitable opening 82^a through which said tube extends and the top end of said arm carries a button 82^b on which appears the word "Off". A leaf spring 83 on 20 the rear face of the wall 4 engages and holds the arm in its normal forward position. With the tube 22 in its forward position it is only necessary to push the button 82^b rearwardly when the said arm which is in front of the 25 shoulder 22^a will shift the same rearwardly and release the "on" arm 34^c of the escapement and thereafter be in a position to catch and stop the "off" arm 34^b of the escapement.

Assume that it is desired to energize a certain piece of mechanism at 9:15 a. m. and to de-energize it at 9:30 a. m. so that it automatically comes "on" at 9:15 a. m. and comes "off" at 9:30 a. m. Two plugs 73 would be used and one inserted in that hole 16 in line 30 with the 9:15 a. m. markings on the dial 13 and the other is inserted in that hole 15 in line with the 9:30 a. m. markings on said dial. Upon the contact finger or plane 77^a reaching the plug 73 in the said outer hole 16 35 the switch in the casing 35 would be closed or brought "on" as before described and when the finger or plane 78^c reaches the plug 73 in the inner hole 15 said switch would be opened or brought "off" as before described. If 40 no further on or off period is desired and no other plugs 73 inserted in any other holes 15 and 16, it is apparent that after a lapse of twelve hours or one complete cycle of the indicator 21, the operation would be repeated 45 at 9:15 p. m. and 9:30 p. m. To prevent such a repetition in each complete cycle of operation of the indicator I provide the following: Supported in the casing wall 4 and plate 9 in the left hand side of the casing as viewed 50 from the front is a shaft 85 parallel with the spindle shaft. Loose on said shaft is a bushing 86 and to the rear end of said shaft is fixed an arm 87 and to the front end of said shaft is fixed a collar 88. On the free end 55 of said arm is a laterally extending tooth or pin 87^a which projects rearwardly through a suitable opening in the plate 9 to overhang the disc 19 with notch 19^a hereinbefore referred to. A coiled spring 89 embraces the 60 portion of the shaft 85 forward of the col-

lar 88 and has one end fixed to said collar and its other end fixed to the casing wall 4 in a manner causing said tooth 87^a to yieldingly bear upon the periphery of the disc 19. A latch is secured to the bushing 86 and includes a short top arm and a long bottom arm 86^a and 86^b respectively, the long bottom arm including a shoulder 86^c in its top edge all as best shown in Fig. 24. A spring 90 carried on the front face of the lever 87 75 urges said latch in a counter clockwise direction and the top or shoulder latch arm 86^a is held up against a pin 87^b on the front face of the lever 87. 91 indicates a lever pivoted at a point between its ends as at 92 on the 80 front face of the plate 9. The top end of said lever is formed with a head 91^a for easy manipulation and which extends up through an opening 3^c in the casing wall 6 near the top thereof. On one face of said lever head is 85 depicted an arrow indicating the direction in which it should be manipulated, and this is in a clockwise direction as shown in Figs. 1, 13 and 20. A spring 93 fixed at one end to the top arm of the lever and to a fixed part 90 in the plate 9 normally holds it in one position engaged against a pin 93^a on the plate 9. On the rear side of the bottom arm of said lever are two rearwardly extending upper and lower pins 91^b and 91^c respectively, between which normally extends the free end 95 of the longer latch arm 86^b. The free end of said bottom arm of the lever is offset laterally and then forwardly to provide a finger 91^d which is adapted to project into a position to be engaged by a second pallet 34^c on the "off" escapement arm or blade 34^b, said pallet being offset forwardly and to that side of said blade or arm opposite the pallet 34^a.

When the lever 91 is in the inoperative position, that is when the "off" arm 34^b of the escapement is locked by the finger 91^d, the spring 93 is holding the upper part of said lever against the stop pin 93^a, and the pin 91^c on said lever is engaged against the under 100 side of the long latch 86^b; the arm 87 being in a position wherein its pin 87^a just clears the periphery of the disc 19. In other words when the escapement arm 34^b is locked by the finger 91^d the disc follower pin 87^a is free of 105 the disc so that the pin 87^a is unable to catch in the disc notch 19^a as the notch passes the same in the rotation of the disc. The function of the pin 91^c is to hold said lever in this 110 position by striking the latch 86^b as it moves counter clockwise to off position. The spring 89 is then held inoperative by the more powerful spring 93. As soon as the lever 91 is moved clockwise to operative position, the pin 91^c moves away from the latch permitting 115 the spring to press the pin 87^a against the periphery of the disc 19. When the pin 87^a enters the notch 19^a in the rotation of the disc, the pin 87^a releases the lever 91 and it is moved to engage the stop pin 93^a when the 120 125 130

pin 91^c strikes the end of the long latch 86^b and raises the pin 87^a free of the disc 19 as before.

In Fig. 1 I have illustrated the device as controlling the "A" battery circuit 95 of a radio receiving set 96 whereby the "off" and "on" periods of broadcast deceptions may be readily brought about while in Fig. 2 I have shown the device as controlling the conductor 10 of a battery of electric lamps 97 such as used in store windows or display sign illumination, to control the "off" and "on" periods thereof.

In Figs. 25, 26 and 27 I have shown a modified form of the invention in which there is substituted for the clock-mechanism 55 heretofore described as driving the impulse control, an electro-magnetic means intended to operate on the regular sixty impulses per hour such as employed in synchronized clock systems. In said figures 57^x indicates the impulse escapement shaft carrying the escapement arms 53 and 54 before described. Fixed to this shaft is a pinion 52^x meshing with a gear 26^a on the disc 24. An auxiliary spring barrel 100 is secured to said shaft to house a spiral flat spring 101 the outer end of which is fixed to said barrel and the inner end of which is fixed to a sleeve 102 on said shaft. Carried on said sleeve is a gear 103 meshing 20 with a pinion 104 secured to a step by step rotative shaft 105 and which corresponds with the shaft 57 before described. Said shaft carries a cam 67^x and a knob 68^x similar to and for the same purpose as the cam 67 and knob 25 68 before described. A ratchet wheel 106 is fixed on the shaft 105 to the rear of the casing wall and rockable on said shaft is an armature 107 including an arm 107^a to which is pivoted a ratchet feeding pawl 107^b. A coiled spring 30 108 connects the arm 107^a with a fixed part of the casing wall 4 and holds it up against a pin 109 projecting from said wall. Also mounted on said wall is a ratchet holding pawl 107^c to prevent unwinding of the spring 101. A rocking motion in one direction 35 against the action of the spring 108 is produced by a pair of electro-magnets 111 mounted on a suitable bracket on the rear wall 4 of the casing. There are fifteen teeth on the ratchet 106, one for every minute so that for each impulse delivered to the magnets, the ratchet is advanced one tooth and as the ratio of the gearing 103 and 104 is as two is to one the spring 101 is wound up half a turn for 40 every turn of the ratchet wheel 106 and for every turn of the cam 67^x the escapement makes a half a revolution thus unwinding the spring a half a turn and in this way it is always maintained wound up within half a 45 turn.

With such a construction the main spring 27 is employed to actuate the electrical snap switch in the casing 35 and therefore there is attached to the spring barrel 25^a (see Fig. 28) a gear 26^b which meshes with a pinion 34^x

on shaft 34 and this in turn drives the switch in the casing 35 as before. The main spring winding gear 29^x is operatively engaged by a pinion 30^x on a winding shaft 31^x having a holding pawl and ratchet 28^x.

70

In operation, the desired number of plugs 73 may be inserted in the desired holes 15 and 16 in line with the proper indications for the desired time periods. Each fifteen minutes the indicator 21 and the lever plate 75 74 receives an impulse in a clockwise direction. If the elapsed time period desired between the "on" and "off" operation happens to be for a part only of a fifteen minute period, this may be compensated for by turning the knob 68 in one direction or the other whereby the lever 70 is depressed at the proper time and the escapement arms 53 and 54 are released to permit movement of the disc 24 and snap switch in the casing 35.

85

The device may be manually set in motion to open and close a circuit at any time, simply by moving either the spring arm 82 or stem 81 to actuate the tube 22. Upon actuating the lever 91, the device is set in an "on" 90 position and will not repeat at the end of a twelve hour period after operation, since the notch 19^a trips said lever out, at the end of each 12 hour period.

The device is compact in size and has the 95 appearance of an ordinary household alarm clock and is indeed portable. The dial being stationary permits of a ready reading and eliminates errors in the desired distribution of the plugs. The device is positive and accurate in operation and may be readily operated by the average layman and does not present the appearance of a laboratory instrument but one familiar in every household.

100

While in describing my invention, I have referred in detail to the form, construction and arrangement of the parts thereof, I do not wish to be limited thereto except as may be pointed out in the appended claims.

110

I claim as my invention:

1. A time switch embodying therein a nonrotative control dial, a rotative indicator operatively associated therewith, means for imparting an impulse movement to the 115 indicator, an escapement mechanism controlling the operation of said impulse means, a switch driven by said escapement, a pallet for controlling the escapement mechanism, and means for actuating the pallet in timed relation with definite positions of said indicator.

120

2. A time switch embodying therein a nonrotative control dial, a rotative indicator operatively associated therewith, means for imparting an impulse movement to the indicator, an escapement mechanism controlling the operation of said impulse means, a switch driven by said escapement, a pallet for controlling the escapement mechanism, and means for manually actuating the pallet.

125

130

3. A time switch embodying therein a non-rotative control dial, a rotative indicator operatively associated therewith, means for imparting an impulse movement to the indicator, an escapement mechanism controlling the operation of said impulse means, a switch driven by said escapement, a pallet for controlling the escapement mechanism, means for actuating the pallet in timed relation with definite positions of said indicator and other means manually operable for actuating the pallet independent of said first mentioned pallet actuating means. 55
- 10 4. A time switch embodying therein, a non-rotative control dial having time divisions thereon, a rotative indicator associated therewith, means for imparting an impulse movement to the indicator from one time division to the other, an escapement controlling said impulse means, a pallet controlling said escapement, plugs adapted to be positioned in said dial in predetermined arrangement with said time divisions thereon, and means actuated upon engagement with said plugs for actuating the pallet. 60
- 15 5. A time switch embodying therein, a non-rotative control dial having time divisions thereon, a rotative indicator associated therewith, means for imparting an impulse movement to the indicator from one time division to the other, an escapement controlling said impulse means, a pallet controlling said escapement, plugs adapted to be positioned in said dial in predetermined arrangement with said time divisions thereon, and means including a single and a compound lever movable with the indicator and operable upon engagement with said plugs to actuate the pallet. 65
- 20 6. A time switch embodying therein, a non-rotative dial, a rotative indicator operatively associated therewith, means for imparting an impulse movement to the indicator, an escapement mechanism for controlling the operation of said impulse movement means, and means for preventing the repeating action of said escapement after a complete cycle of operation of said indicator. 70
- 25 7. A time switch embodying therein, a non-rotative dial, a rotative indicator operatively associated therewith, means for imparting an impulse movement to the indicator, an escapement mechanism for controlling the operation of said impulse movement means, manually set means normally disengaged from the escapement and operable in timed relation with the indicator to be automatically released and to engage the escapement mechanism and prevent a repeating thereof after a complete cycle of operation of the indicator. 75
- 30 8. A time switch embodying therein, a main dial having time divisions, thereon, an indicator operatively associated therewith, a shaft on which said indicator is mounted and means for setting the indicator including a collar fixed on said shaft and a collar loose on said shaft and capable of being operatively engaged with the first collar to rotate the same in one direction only. 80
- 35 9. A time switch embodying therein, a dial having time divisions thereon and inner and outer rows of openings to receive plugs in line with certain of said divisions, a step by step rotative member carrying levers to engage said plugs, means for imparting an impulse movement to said member including a disc, and means for advancing or retarding said disc with respect to said member. 85
- 40 10. A time switch embodying therein, a dial having time divisions thereon and inner and outer rows of openings to receive plugs in line with certain of said divisions, a step by step rotative member carrying levers to engage said plugs, means for imparting an impulse movement to said member including a disc, an escapement driven by said disc, a lever for holding and releasing said escapement and means associated with said lever and including a cam for controlling said holding and releasing of the lever with respect to said escapement. 90
- 45 11. In combination with a rotary snap switch, means normally acting to rotate said switch and including a motor and escapement, means for normally holding the escapement against operation, a step by step rotatable member, a control dial with openings therein, control devices adapted to be inserted in openings in said dial and means operative upon engagement by said step by step rotating member with said control fingers for actuating the means normally holding the escapement to release it so that the same will actuate the switch. 95
- 50 12. In testimony whereof, I have hereunto set my hand, this 7 day of September, 1926. 100
- CHARLES M. PEACOCK. 105
